ROLLING DOOR CONSTRUCTION

Nathan Michelman, Brooklyn, N. Y.

Application August 12, 1944, Serial No. 549,228

5 Claims. (Cl. 160—133)

This invention relates to rolling doors, of the type comprising a flexible curtain formed of a number of sections interconnected for relative hinged movement and adapted to be wound upon a rotatable drum suitably located at the head of the doorway. The invention is specifically directed to the provision of a rolling door of the aforementioned character adapted for use in buildings, industrial structures, garages, and the like, which comprises a flexible curtain incorporating windows suitably arranged therein to permit viewing of the interior of the building to which the rolling door is applied and illumination of the same.

An object of the invention is to provide an improved construction for a rolling door of the type aforementioned, wherein a plurality of windows are provided at spaced intervals along the length of the flexible curtain, and the hinged interconnected sections forming the flexible curtain are so arranged as to permit of the easy winding thereof upon a suitable non-circular rotatable drum.

Another object of the invention is to provide a flexible curtain comprising alternate rigid window-embodying sections and interconnecting sections, the structure being such that, when the curtain is wound upon a non-circular drum, the window-embodying sections will form series of superimposed parallel units.

A further object of the invention is to provide a rolling door construction comprising a polygonal winding drum and a flexible curtain incorporating window-embodying sections of uniform width interconnected by sections of different width, whereby, in the winding of the curtain upon the drum, all the sections of the curtain will dispose themselves in parallel relation to sides of the polygonal drum.

These and other related objects will become apparent by the following description of a preferred embodiment of the invention illustrated in the drawing, wherein:

Fig. 1 is a side elevational view of a rolling door according to the invention, illustrating the structure of the flexible curtain forming part of the door and the arrangement of the sections of the curtain upon the drum.

Fig. 2 is a front elevation of the structure of Fig. 1.

Fig. 3 is a perspective view of one of the window-embodying sections of the curtain.

Fig. 4 is a vertical section, on line 4—4 of Fig. 3, illustrating the structure of a window-embodying section.

Referring now in detail to the drawing, 10 indicates a counterbalanced rotatable shaft of the kind usually provided in rolling door constructions, which is suitably supported at the head of the doorway and carries, for rotation therewith, a drum 12 upon which a flexible door or curtain may be wound, the drum being, in the embodiment illustrated, hexagonal in cross-section.

10 The door or curtain consists of a number of metal sections the length whereof is substantially equal to the length of the winding drum 12, and which are hingedly interconnected at their ends to render the curtain articulated and adapted to be wound upon said drum. Specifically, the curtain consists of a number of rigid window-embodying sections or units 16 and a number of connecting sections 18 alternate with the units 16 in the manner and for the purpose that will hereafter be described.

The window-embodying units 16, which are all of uniform width, as shown in Fig. 1, comprise a flat portion 20 formed at its ends with oppositely coiled portions 21, 22. As will be observed, said flat portion 20 is substantially equal in width to the longer sides 23 of the polygonal drum 12, and is provided with a plurality of identical openings or windows 24, uniformly spaced from each other along said portion 20. Frames 25, secured to the flat portion in any suitable manner, are provided for mounting glass panes 26 in juxtaposition to the windows 24. In the embodiment illustrated, there are shown four rectangular windows 24 and associated frame and glass panes for each section 16; it will however be understood that the number and shape of the windows and associated elements may be varied, as desired.

30 The connecting sections 18, alternate with the sections 16, are equal in length to these latter, and are likewise formed with oppositely coiled portions 28, 29 engaging the coiled portions of adjacent window-embodying units and adapted to form with these latter hinge members permitting relative angular movement of the various sections, as required for the winding of the curtain upon the drum. Preferably, said connecting sections 18 are rigid and have a flat wall intermediate the coiled portions thereof similarly to the window-embodying units 16, but they may be made, if desired, of substantially flexible corrugated metal sheet. The width of the sections 16, however, is not uniform throughout the length of the curtain, but increases from the top to the bottom of the curtain, in the manner that will be described, for the purpose of permitting the

window-embodying units 16 to dispose themselves in groups of units parallel to sides of the polygonal drum 12, when the curtain is wound upon the drum, as will hereafter become apparent. The curtain is formed, throughout its length, of alternate units 16 and sections 18, though the windows may be omitted in certain of the units located near the top and the bottom of the curtain, for obvious reasons, the structure remaining otherwise unchanged.

The curtain is secured, at one end thereof, to the drum 12 in any suitable manner, as by means of an initial short link 30 riveted or bolted to the drum, as shown at 31. Assuming that the first hinged or free section of the curtain is to be one of the units 16, the link 30 is fastened to one of the short sides 32 of the polygonal drum 12 in such a position that the flat portion 20 of the unit 16 is superimposed to the adjacent long side 23 of the drum, while the coiled portions of the unit project laterally thereof. Since the curtain is formed of alternate units 16 and sections 18, the next short side 32 of the drum will have superimposed thereon the first section 18, which is made substantially equal in width to said short side 32 whereby the second unit 16 is allowed to overlie, with its flat portion 20, the following long side 23 of the drum, in the manner hereinbefore described.

As can be seen in Fig. 1, the second section 18 is identical to the first, but the next section following the third unit 16 is of greater width to permit the adjacent unit 16 to superimpose itself to the first unit and to assume a position in parallel relation to this latter and to the underlying side of the drum. As will therefore be apparent, in order to have series of aligned units 16 superimposed upon sides of the drum in parallel relation thereto, the width of the sections 18 is increased with each winding of the curtain upon the drum, that is in proportion to the increase in the distance of the sections from the axis of the drum, or, in other words, for each three alternate units 16 and sections 18 there is an increase in the width of these latter.

The structure formed in this manner permits to provide series of windows incorporated in rigid units so that glass panes may be associated with the windows without danger of breakage in the operation of the door, requires a minimum of space for the winding of the curtain and insures a smooth and easy operation of the door due to the advantageous arrangement of the sections of the curtain and associated drum.

While I have described my invention substantially with reference to a preferred embodiment thereof, it is to be understood that changes and modifications may be made in the structure described and illustrated in the drawing without departing from the spirit of the invention or exceeding the scope of the claims.

I claim:

1. A rolling door comprising a rotatable polygonal drum and a flexible curtain adapted to be wound upon said drum, said curtain comprising a plurality of window-embodying units of uniform width and a plurality of sections alternating with said units, the width of said sections increasing with the distance of the sections from the axis

of the drum when wound thereon, whereby, in the winding of the curtain upon the drum, the window-embodying units are caused to dispose themselves in parallelism with sides of the drum.

5 2. A rolling door comprising a rotatable polygonal drum and a curtain comprising a plurality of rigid window-embodying units of uniform width and a plurality of sections alternating with said window-embodying units and hingedly interconnected thereto, to form a flexible curtain adapted to be wound upon said drum, the width of said sections increasing in proportion to the increase in the distance of the sections from the axis of the drum when wound thereon, whereby, 10 in the winding of the curtain upon the drum, the window-embodying sections are caused to dispose themselves in parallelism with sides of the drum.

15 3. A rolling door comprising a rotatable polygonal drum and a curtain consisting of a plurality of rigid units of uniform width, each embodying a number of windows of equal dimensions, and a plurality of sections alternating with said window-embodying units and hingedly interconnected thereto, to form a flexible curtain adapted 20 to be wound upon said drum, the width of said sections increasing in proportion to the increase in the distance of the sections from the axis of the drum when wound thereon, whereby, in the 25 winding of the curtain upon the drum, the window-embodying sections are caused to dispose themselves in parallelism with sides of the drum.

30 4. A rolling door comprising a rotatable hexagonal drum, a flexible curtain connected at one end thereof to said drum and adapted to be wound thereon, said curtain comprising a plurality of window-embodying units of uniform width and a plurality of sections alternating with said window-embodying units and hingedly connected thereto, the width of said sections increasing 35 for each three alternate window-embodying units and sections, whereby in the winding of the curtain upon the drum, the window-embodying units will form groups of aligned units superimposed upon sides of the hexagonal drum and parallel thereto alternating with groups of sections superimposed upon the remaining sides of the drum.

40 5. A rolling door comprising a rotatable hexagonal drum, and a curtain consisting of a plurality of rigid units of uniform width, each embodying a number of windows of equal dimensions, and a plurality of sections alternating with said window-embodying units and hingedly connected thereto, to form a flexible curtain adapted 45 to be wound upon said drum, the width of said sections increasing for each three alternate window-embodying units and sections, whereby, in the winding of the curtain upon the drum, the window-embodying units will progressively superimpose themselves upon sides of the hexagonal drum to form groups of aligned units parallel to said sides of the drum and the sections will progressively superimpose themselves upon the remaining sides of the drum to form groups alternating with the groups of window-embodying units.

NATHAN MICHELMAN.
